Primary Examiner — Katrina A Betton(74) *Attorney, Agent, or Firm* — Dunlap Bennett & Ludwig, PLLC(57) **CLAIM**

The ornamental design for a mobile food vending cart, as shown and described.

DESCRIPTION

FIG. 1 is a front right top perspective view of the mobile food vending cart, showing my new design;

FIG. 2 is a front left top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The evenly-sized broken lines shown in the drawings depict portions of the mobile food vending cart that form no part of the claimed design.

The unevenly-sized broken line represents the boundary of the claimed design and forms no part of the claimed design. Any portion of the design not shown in the drawings forms no part of the claimed design and is hereby disclaimed.
